R. C. LYTTLE,
GRAVITY CAR CONTROL.
FILED FEB. 23, 1922.

UNITED STATES PATENT OFFICE.

ROY C. LYTTLE, OF CHICAGO, ILLINOIS.

GRAVITY-CAR CONTROL.

Application filed February 23, 1922. Serial No. 538,588.

To all whom it may concern:

Be it known that I, ROY C. LYTTLE, a citizen of the United States, and a resident of Chicago, in the county of Cook and State 5 of Illinois, have invented a new and useful Improvement in Gravity-Car Controls, of which the following is a full, clear, and exact description.

My invention relates to improvements in 10 gravity car controls, and it consists in the combinations, constructions, and arrangements herein described and claimed.

An object of my invention is to provide a 15 gravity car control which is adapted to automatically slow up a car, such as a freight car, as the latter passes thereover.

A further object of my invention is to 20 provide a device of the type described in which the braking force applied to the car is proportional to the weight of the car.

A further object of my invention is to 25 provide a device of the type described in which the braking force may be varied at will.

30 A further object of my invention is to provide a device of the type described which is adapted to effectually apply a braking force simultaneously to all of the wheels of a car which pass thereover.

35 A further object of my invention is to provide a device of the type described which may be readily installed in a track of ordinary construction, and which is especially adapted for use in terminals or yards.

40 A further object of my invention is to provide a device of the type described which is simple in construction, efficient for the purpose intended, and which is not likely to easily get out of order.

45 Other objects and advantages will appear in the following specification, and the novel features of the invention will be particularly pointed out in the appended claims.

My invention is illustrated in the accompanying drawings, forming part of this application, in which—

Figure 1 is a diagrammatic view of a railroad track, showing places where two of the devices could be effectually disposed,

50 Figure 2 is an end elevation of the device, and

Figure 3 is a section along the line 3—3 of Figure 2.

In carrying out my invention, I provide 55 a movable platform 1 which carries a section of an ordinary railroad track 2. The

section of the track is disposed in a track of ordinary construction, and a car, which is carried by the ordinary track, is adapted to pass over this section. When the car is 60 disposed on the section, the weight thereof will actuate a means hereinafter described, which will automatically apply a braking force to the car in proportion to the weight of the car.

65

Means by which the foregoing is accomplished consists of a well 3 which is disposed beneath the track, and in which the platform 1 is adapted to move. The platform 1 entirely encloses the well 3, thereby 70 preventing dirt or the like from entering the well and interfering with the mechanism disposed in the well.

75

The well 3 is enclosed by cement walls and floor 4, or the like. As clearly shown in Figure 2, the level 75 of the ground lies in the same plane as the platform 1, and the platform 1 is normally disposed at the top of the well 3. The platform 1 may consist of a plurality of trans-

80

verse planks which are secured to longitudinally extending beams 5. These beams are supported by rods 6 which are slidable in housing 7, the housing being carried by the floor 4. The platform 1 is preferably one and one-half times the length of the 85

85

ordinary freight car, although it is obvious that it may be of any length desired. The supporting rods 6 are disposed approximately eight to ten feet apart so as to provide a rigid supporting surface to the plat- 90

90

form 1. Tension springs 8 are disposed around the rods 6, and are adapted to support the platform 1 so as to normally keep the platform in a plane parallel with the plane of the ground. The rods 6 also carry 95

95

nuts 9 which abut the housings 7 so as to prevent the movement of the platform 1 above the full line position shown in Figure 2. The springs 8 are of such strength as to respond to an empty box car. A much 100

100

heavier spring 10 encircles the spring 8, and is adapted to be supported by the housing 7. It will be seen that this spring is not as long as the spring 8. In other words, the platform 1 will have to be moved down- 105

105

wardly a slight distance before the top of the spring 10 engages with the under side of the beam 5. This construction provides a simple and effective means by which a light freight car, or the like, will actuate the mechanism, and a heavy freight car, or the like, will also actuate the mechanism,

110

but will not move the platform much beyond the movement that the light freight car imparts thereto. In other words, the rail sections carried by the platform 1 are never disposed so low as to prevent the car from moving off from the platform and onto the regular track.

The mechanism which automatically applies the brakes consists in a plurality of 10 cylinders 11 which have pistons 12 mounted therein. A compressed air tank 13 is connected to the cylinders 12 by means of an air pipe 14 and branch air pipes 15. The pipes 15 communicate with the pipe 14 and with 15 the cylinders 11. These pipes are controlled by the valve which has an arm 16. It will be apparent that when the arm 16 is actuated, it will open the valve in its respective pipe 15 so as to permit the air to flow from 20 the pipe 14 into the cylinder 15, whereby the piston 12 is moved upwardly. I prefer to have the number of cylinders 11 equal to the number of pairs of supporting rods 6, but I do not care to be confined to this specific 25 arrangement. Each of the arms 16 is operatively connected to the platform 1 so that when the platform is moved slightly in a downward direction, the arms will be actuated so as to permit air to enter the cylinders 11.

Means by which the arms 16 are actuated comprises links 17 which are connected to the beams 5 and to bell crank levers 18, the bell crank levers being carried by supports 35 19. The free ends of the bell crank levers are operatively connected to the arms 16 by means of links 20. It will therefore be apparent that the downward movement of the links 17 will swing the arms 16 from the full 40 line position to the dotted line position shown in Figure 2, whereby air is permitted to enter the cylinders 11. The piston 12 carries a piston rod 21, which in turn has links 22 secured thereto. The free ends of the 45 links 22 are supported by links 23, these links having their free ends pivotally carried by the platform 1. The free ends of each set of links 22 are secured to a longitudinally extending member 24, such as a 50 rail, this member being normally disposed on the inside of the tracks 2 and slightly above the plane of the latter. The members 24 are substantially as long as the platform 1, and are adapted to be moved outwardly 55 by the links 22 when the platform 1 is moved downwardly. It is therefore obvious that the members 24 will frictionally engage the inner sides of all of the wheels of the car which are being carried by the platform 1. 60 From the foregoing description of the various parts of the device, the operation thereof may be readily understood. In Figure 1, I have shown a diagrammatic view of a terminal in which there is a slight down grade, 65 such as at 25. Assume that the car 26 has

just been released by a switch locomotive (not shown) and is moving in the direction of the arrow. Also assume that a switch in the track is disposed at 27. It is obvious that the car 26, as it moves down the grade 70 25, will increase in speed, and will move along the lower portion 28 of the track at a relatively great speed. If a group of cars were already disposed on the portion 28 of the track, the car 26 would strike the latter 75 with a relatively great force, which would jar the contents of the car, and subject the car to undue stresses. Furthermore, the car 26 might be going at such a speed as to become derailed when being switched at the 80 point 27. In the system thus outlined, I could dispose one of my devices at the down grade 25, and another device after the switching point 27, such as indicated at x and y . It will now be apparent that when 85 the car 26 passes over the device situated at x , the braking mechanism hereinbefore described will cause the members 24 to frictionally engage the wheels 29 of the car, whereby the car is retarded in its speed. 90 As the car 26 passes from the device situated at x , it will be going at a much slower speed and will therefore not be likely to be derailed when being switched. After the car 95 has passed the switching point, it is further retarded in its speed by the device situated at y , whereupon the movement thereof will be relatively slow, so that when the car engages with the train of cars (not shown) on the portion 28 of the track, it will not strike 100 these cars with a great force. It will therefore be seen that by providing the foregoing track with the devices, the switching of cars will be accomplished with the minimum amount of damage. The foregoing system 105 is given as a typical example of how the devices may be effectively disposed in a terminal of known construction. It is obvious that the devices may be disposed in terminals which are on relatively flat ground instead of hilly ground, as hereinbefore described.

From the foregoing it will be observed that I have provided a device which is efficient in operation, and which is adapted to 110 effectually apply a braking force to a car which passes thereover. It will further be noted that the movement of the platform 1 is substantially the same whether the car passing thereover is heavy or light. It will 115 also be apparent that a greater movement is imparted to the platform 1 when a heavy car passed thereover, whereby a greater braking force is applied to wheels of the car. As heretofore stated, the device is 120 relatively simple in operation, and is not likely to easily get out of order.

I claim:

1. The combination with a track, of a 125 movable track section constituting a part 130

of said main track, said track section being adapted to move slightly downwardly with respect to the main track when a car is placed thereon, and means actuated by the movement of said car for simultaneously applying a braking force to the inner sides of all of the car wheels.

2. The combination with a track, of a movable track section constituting a part 10 of said main track, said track section being adapted to move slightly downwardly with respect to the main track when a car is placed thereon, and means actuated by the movement of said car for simultaneously 15 applying a braking force to the inner sides of all of the car wheels, said means being adapted to apply a braking force to the car wheels in proportion to the weight of the car.

20 3. A device of the type described comprising a horizontal track supporting platform adapted to move in a vertical direction, and means actuated by the movement of said platform for applying a braking 25 force to the inner sides of all the wheels of a freight car when supported by said platform.

4. A device of the type described comprising a track supporting platform, rods 30 yieldingly supporting said platform and being adapted to be moved in a vertical direction, braking members disposed inside of and parallel with the tracks, a pressure cylinder, a piston in said cylinder and being operatively 35 connected to said braking members, whereby when said piston is actuated, said braking members will be moved away from each other, a valve for said cylinder, said valve being operatively connected to said platform, whereby a downward movement of 75 said platform will actuate said valve.

said platform, whereby a downward movement of said platform will actuate said valve. 40

5. A device of the type described comprising a track supporting platform, platform supporting members, rods slidably 45 carried by said members and being connected to said platform, a relatively light tension spring disposed around each rod and between said supporting members and said platform, and a relatively heavy tension 50 spring disposed around each light spring and being carried by said supporting members, said heavy springs terminating a spaced distance from said platform.

6. A device of the type described comprising a track supporting platform, platform supporting members, rods slidably carried by said members and being connected to said platform, a relatively light tension spring disposed around each rod 60 and between said supporting members and said platform, a relatively heavy tension spring disposed around each light spring and being carried by said supporting members, said heavy springs terminating a 65 spaced distance from said platform, braking members disposed inside of and parallel with the tracks, a pressure cylinder, a piston in said cylinder and being operatively connected to said braking members, whereby when said piston is actuated, said braking members will be moved away from each other, a valve for said cylinder, said valve being operatively connected to said platform, whereby a downward movement of 70 said platform will actuate said valve. 75

ROY C. LYTTLE.
